UNITED STATES PATENT OFFICE.

IGNATZ SALZ, OF NEW YORK, N. Y., ASSIGNOR TO SALZ BROS. INC., A CORPORATION.

DESIGN FOR A COMBINATION DESK SET.

Application filed June 21, 1926. Serial No. 18,108. Term of patent $3\frac{1}{2}$ years.

To all whom it may concern:

Be it known that I, IGNATZ SALZ, a citizen of the United States, and residing at New York city, in the county of New York and State of New York, have invented a new, original, and ornamental Design for Combination Desk Set, of which the following is a specification, reference being had to the accompanying drawings, forming part hereof.

The figure is a perspective view of the combination desk set.

I claim:

The ornamental design for a combination desk set as shown.

IGNATZ SALZ.
